UNITED STATES PATENT OFFICE.

RICHARD WEBB BURNETT, OF MONTREAL, QUEBEC, CANADA.

CAR-UNDERFRAME.

1,300,340.

Specification of Letters Patent. Patented Apr. 15, 1919.

Application filed November 30, 1914. Serial No. 874,681.

To all whom it may concern:

Be it known that I, RICHARD WEBB BURNETT, a citizen of the United States, residing at Montreal, in the Province of Quebec and Dominion of Canada, have invented a certain new and useful Improvement in Car-Underframes, of which the following is a full, clear, concise, and exact description, reference being had to the accompanying drawings, forming a part of this specification.

This invention relates to improvements in car under frames.

An object of the invention is to provide an under frame structure for cars having wooden center sills and which is particularly adapted for repairs.

Another object of the invention is to provide a construction suitable for repairing cars having wooden center sills and which is adapted to have attached thereto stop castings of the type generally employed with wooden draft sills.

In the drawing forming a part of this specification, Figure 1 is a longitudinal vertical sectional view of an end portion of a car taken along the longitudinal center thereof. Fig. 2 is a horizontal sectional view, the lower half of which is taken substantially on the section line 2—2 of Fig. 1 and the upper half on the section line 2^A—2^A of Fig. 1, said Fig. 2 showing a draft gear applied, the parts of the latter being shown in top plan view. Figs. 3 and 4 are enlarged detail sectional views taken respectively on the lines 3—3 and 4—4 of Fig. 1. Fig. 5 is a sectional view, similar to Fig. 3, showing another form of my invention. Fig. 6 is a view, similar to Fig. 1, showing another form of my improvements, and Fig. 7 is a horizontal sectional view taken substantially on the line 7—7 of Fig. 6 and showing also a tandem spring draft rigging in position, the parts of the latter being shown in top plan view.

Referring now to Figs. 1 to 4 inclusive, 10—10 denote wooden center sills, 11 an end sill, 12 a buffer or dead block and 13 a body bolster. Secured to the inner faces of each of the center sills 10, is a plate 14, each of which has an upper vertical portion 15, lower vertical portion 16, the latter being offset from the upper portion 15 by means of a horizontal web 17 which fits against the under face of the sill. The portions 15 are secured to the sills 10 by transversely extend-

ing bolts 18 which, at their outer ends, pass through plates 19 on the outer sides of the sills. As shown in Figs. 1 and 2, the portions 15 are provided with inturned flanges 20 at their front ends which abut the rear face of the end sill 11 and are secured thereto by bolts 21. The portions 15 are also notched or cut away as indicated at 22, to pass by the body bolster 13. Secured to the outer face of each of the depending portions 16 are 65 upper and lower angles 23 and 24 which brace and strengthen the plates 14. As will be understood, the angle irons 23 and 24 are suitably offset as indicated at 25—25 in Fig. 1 at the free ends thereof to conform to the 70 narrowed width of the portions 16 where the same extend beneath the end sill and buffer block. The horizontal flanges of the upper angle irons 23 are secured to the sills 10 by vertical sill bolts 26. To further strengthen 75 the plates 14 and also to assist in absorbing the buffing shocks, I provide a U-shaped plate having side arms 27 riveted to the portions 16 and a transversely extending portion 28 which abuts the front side of the body bolster 13. The depending portions 16 of the plate 14 serve as draft sills or draft members for the stop or side castings 29—29, having mounted therebetween a draft gear which, as shown, is of the tandem variety and comprises followers 30, springs 31, yoke 32 and draw bar 33.

In the construction shown in Fig. 5, the plates 114 have the upper portions 115 bolted to the outer sides of the center sills, the transversely extending securing bolts 118 therefor passing through wear plates 119 on the inner sides of the sills. In this construction, the vertical sill bolts 126 pass through the horizontal webs 117 of the plates instead of 85 through an upper angle iron in the construction shown in the first four figures. In other respects, the structure shown in Fig. 5 corresponds to that shown in Figs. 1, 2 and 4.

In Figs. 6 and 7, the construction is similar 100 to that shown in the first four figures, except that the plates 214 are provided with offsets or indentations 40—40 in which are adapted to be seated the lugs 41 formed on the back faces of the stop castings 229, which lugs 41 are those ordinarily found on stop castings which are employed with wooden draft sills and are seated in notches cut in the wooden draft sills. With this construction, in repairing a car having wooden draft 105 110

sills, my improved plates 214 are substituted therefor, the same having means provided for re-attaching the stop castings used with the wooden draft sills. In the construction 5 shown in Figs. 6 and 7 the angle irons which brace the draft member portions of the plates 214 are also offset as indicated at 42—42 where the angle irons pass by the offsets 40 in the members 214.

10 From an inspection of Figs. 3, 4 and 5, it will be seen that the plates 14 and 114, which may be said to be of Z-shape, in combination with the plates 19 and 119 form a box-like casing for the wooden center sills, which I 15 have found to be of great practical value in repairing cars, especially when the sills have been split from any cause. With my arrangement it becomes unnecessary to remove or replace such split sills, since the application 20 of the inner and outer and bottom plates thereto, when tightly bolted, form a rigid and strong casing therefor.

I claim:—

1. In an underframing for cars, the combination with wooden center sills, end sill, 25 and body bolster, of plates secured to the inner sides of said center sills and having offset depending portions disposed beneath said sills, the offset depending portions being connected to the upper portions by integral horizontal webs, separate plates secured to the outer faces of said sills, angle irons secured to the outer upper portions of said offset portions of the first named plates, said angle 30 irons engaging the under sides of said sills, horizontal bolts extending through said plates on the sides of said sills; and vertical bolts extending through said angle irons and said sills, whereby the center sills are provided with a substantially boxlike casing. 35

2. In an under-frame for railway cars, the combination with wooden center sills, end sill, and body bolster, of plates secured to the inner faces of said center sills, each of 40 said plates extending from the end sill to a point in the rear of the bolster and provided with a depending offset portion disposed beneath the sill, said depending portion serving as a draft sill, upper and lower angle irons secured to the outer faces of said depending portions of the plates, the upper ones of said angle irons being bolted to the center sills. 45

3. In an underframe construction for cars, 50 the combination with a wooden center sill, of a plate secured to one side of said sill, said plate having a depending portion below the sill to which is adapted to be attached a stop casting, a reinforcing member 55 secured to the depending portion of said plate and abutting the bottom face of said sill, another plate secured to the opposite face of said sill, horizontal bolts extending through said plates on the sides of said sill 60 and vertical bolts extending through the re-

inforcing member and said sill, whereby the center sill is provided with a substantially boxlike casing adapted to prevent splitting of the sill.

4. In a reinforced wooden underframe 70 for cars having wooden center sills, draft plates secured to the inner faces of the sills and having an outwardly offset portion below the sills, a portion of each draft plate below the sills depending from the offset 75 portion, horizontal angle irons each having one flange secured to the bottom face of one sill, the other flange of each angle iron being secured to the depending portion of the corresponding draft plate just below the sill, the draft plate having an outwardly turned web reinforcing its bottom edge, cheek plates on the depending portions of the draft plates, secured thereto, and means 80 for securing the cheek plates to the inner faces of the depending portions of the draft plates in the form of two rows of rivets, the upper row passing through the vertical web 85 of the angle, the draft plate and the cheek plate. 90

5. A reinforced wooden underframe for cars having wooden center sills, draft plates secured to the inner faces of the center sills, a portion of the draft plates extending below the sills and offset outwardly, horizontal 95 angle irons secured to the upper and lower edges of the depending portions of the draft plates, each upper angle iron having one flange secured to the bottom face of one sill and a vertical flange secured to the 100 depending portion of the corresponding draft plate just below the sill, the other angle iron having a horizontal flange at the bottom of the draft plate and a vertical flange secured to the lower portion of the 105 draft plate, and cheek plates secured to the depending portions of the draft plates, and means passing through the vertical webs of the angle irons, the depending portion of the draft plate and the cheek plates for 110 holding the parts together.

6. As an article of manufacture, a draft arm and center sill reinforcement constructed to be used with cars having wooden center sills, said article comprising draft plates 115 adapted to be secured to the inner faces of the sills and having an outwardly offset portion, a portion of each draft plate depending from the offset portion, horizontal angle irons each having one flange adapted to be secured to the bottom face of one sill, the other flange of each angle iron being secured to the depending portion of the corresponding draft plate, the draft plate having an outwardly turned web reinforcing its bottom edge, cheek plates on the depending portions of the draft plates, secured thereto, and means for securing the cheek plates to the inner faces of the depending portions of the draft plates in the 120 125 130

form of two rows of rivets, the upper row passing through the vertical web of the angle, the draft plate and the cheek plate.

7. In a car underframe reinforcement, the combination with stop castings provided on the outer faces thereof with projecting lugs, of wooden center sills, metal draft plates secured to the faces of said wooden center sills and extending between the end sill and the car bolster, said metal draft plates having portions depending below the wooden center sills and offset beneath the latter, said depending portions of the draft plates being provided on their adjacent faces with recesses within which are received the projecting lugs of the stop castings.

8. In an underframe construction for cars, the combination with a wooden center sill, of a rolled plate secured to one side of said

sill and provided with a depending portion beneath the bottom of said sill, said depending portion being offset from the upper portion and the plate extending continuously from the end sill of the car to a point at the rear of the body bolster, said depending portion of the plate being provided along the lower edge thereof on the outer side with a reinforcing flange, said depending portion of the plate being also provided with outwardly extending offsets adapted to receive the usual lugs formed on the outer sides of the draft rigging stop castings employed with wooden draft sills.
